UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

Application filed March 9, 1928. Serial No. 260,351.

This invention relates to typographical machines, such as linotype machines of the general organization represented in U. S. Letters Patent to O. Mergenthaler No. 436,532, wherein circulating matrices are released by escapements from a magazine or magazines in the order in which their characters are to appear in print and then assembled in line, the composed line transferred to the face of a mold, the mold filled with molten metal to form a slug or linotype against the matrices which produce the type characters thereon, and the matrices thereafter returned thru a distributing mechanism to the magazine or magazines from which they started.

In these machines, the magazines are usually mounted in such manner that they may be quickly removed and replaced by other magazines containing different matrix fonts. Before removing a magazine, however, it is customary to lock the matrices therein; in fact, this is necessary when the escapements are separated from the magazine, as otherwise the matrices would be free to escape therefrom. Hence, the commercial machines are equipped with devices which prevent the removal of the desired magazine until the matrices have been first locked therein. In some instances, as when the magazine is lifted out of engagement with the escapements, the locking devices are arranged to prevent the premature raising of the magazine; while, in other instances, as when the escapements are lowered out of operative relation to the magazine, the locking devices are arranged to prevent the movement of the escapements as distinguished from that of the magazine. In either case, the locking devices referred to are controlled and actuated by matrix locking means, which in locking the matrices in the magazine release it for removal. There are two kinds of matrix locking means now in use, one being in the form of a detachable bar which is inserted and removed endwise thru the edge of the magazine at the right, and the other being in the form of a permanently attached bar mounted on the magazine so as to be movable instantly to active or inactive position.

While the detachable bar is cheap to manufacture and presents other advantages over bars of the permanent type, serious difficulties have arisen in its use in certain commercial machines, particularly those equipped with auxiliary magazines. In the latter class

of machines, the proximity and arrangement of the auxiliary magazines and their associated parts in relation to the main magazines is such that they interfere with the regular manipulation of the locking bars, and it is frequently necessary, in multiple magazine machines, to first raise either the main magazines or the auxiliary magazines as a whole from their last adjusted position in order to insert or withdraw the locking bar and thereafter restore the magazines to their original position. As a result of this condition, which is generally inconvenient and troublesome, the interchange of magazines requires more time than it otherwise would.

The present invention is intended to obviate these and other difficulties and contemplates a detachable locking bar which will present every advantage of the old locking bar but which may be effectively employed and freely manipulated in locking and releasing the matrices of the main magazines on all machines, including those provided with auxiliary magazines. To this end, the parts are so constructed and arranged that the locking bar may be inserted and removed thru the edge of the magazine adjacent the magazine-locking device, which is located at the left instead of the right side of the magazine or the side opposite the auxiliary magazines, the bar being formed with an angular offset portion which is adapted to engage and actuate said device as the bar is moved to and from its active position.

In the accompanying drawings, the invention has been shown merely in preferred form and by way of example, but obviously many alterations and variations may be made therein and in its mode of application which will still be comprised within its spirit. It is therefore to be understood that the invention is not limited to any specific form or embodiment except in so far as such limitations are specified in the claims.

Referring to the drawings:

Fig. 1 is a perspective view of a magazine and parts associated therewith showing the application of the present invention; and

Fig. 2 is a side elevation, partly in section, showing the magazine in operative relation to the escapements and assembler throat.

The matrices X, see Fig. 2, are stored in the channeled magazine A from which they pass into the assembler throat or raceway B under control of the escapements C, the latter

100

105

110

being actuated thru the series of pivoted levers C^1 from the regular keyboard mechanism, not shown. The magazine A is or may be of standard construction, thruout, comprising the upper and lower grooved plates A^1 , A^2 and right and left hand side bars A^3 , A^4 which latter sustain the plates in parallel spaced relation. At the front, the plates A^1 , A^2 are extended by means of the usual 10 heavier plate sections A^5 , A^6 , respectively, which are also fastened to the side bars A^3 , A^4 , the upper section A^5 being formed with the inner longitudinal groove A^7 arranged to register with the regular transverse 15 openings A^8 in the magazine side bars, and the lower section A^6 being recessed or apertured on its under side to receive the grooved portions of the escapement supporting bar C^2 . As shown in Fig. 2, the escapement bar C^2 is 20 fixed to the magazine base frame D, while the magazine is adapted to be lifted out of engagement therewith preparatory to its removal. Consequently, the safety locking device herein illustrated is associated with the 25 magazine rather than with the escapements and is intended to prevent the lifting of the magazine from its base frame until the matrices have first been locked therein. This device is arranged as usual at the left side of 30 the magazine adjacent the side bar A^4 and consists of a latch or lever E disposed in the longitudinal plane of the magazine and pivotally mounted in a suitable bracket E^1 fastened to the base frame D. A light compression 35 spring E^2 , seated in the bracket E^1 and engaging the latch E, serves to maintain the latter resiliently in active position with its rear end directly opposed to a finger F^1 rising from a rock shaft F and adapted to be 40 turned forwardly as the magazine is lifted out of engagement with the escapements C. The rock shaft F is journaled transversely in the base frame D and is provided about midway of its length with a rectangular cam 45 plate F^2 normally disposed in the plane of the base frame D in position to directly engage a longitudinal bar A^9 fast to the magazine ribs A^{10} . With this arrangement, by turning the rock shaft F, the cam plate will 50 be swung upwardly and downwardly and, thru its engagement with the bar A^9 , will raise and lower the magazine relatively to the base frame and the escapement bar C^2 . The rock shaft F is operated manually as usual 55 by means of a pair of side arms F^3 which are detachably mounted on the opposite ends thereof, and may be locked thereto in any suitable manner in order to obtain the purchase required. These arms are adapted to bank 60 upon lateral projections D^1 of the base frame D when swung forwardly to raise the magazine and, at such time, serve not only to support the magazine during its removal but also to facilitate its replacement. The foregoing parts and their mode of operation are 65

similar to those incorporated in the most recent linotype models and in themselves constitute no part of the present invention. For further information, reference may be had to the McNamara Patent No. 1,586,816, dated 70 May 25, 1926.

The present invention is directed specifically to a novel scheme for locking the matrices in the magazine in such manner as to avoid the difficulties pointed out in the opening statement. In the preferred embodiment illustrated, there is employed a detachable bar G which can be inserted into the magazine from the left or at the side opposite from the auxiliary magazines and which is 75 designed to actuate the latch E, as required, in effecting the locking and unlocking of the magazine. As best shown in Fig. 1, the improved bar G in cross section is similar to the regular detachable bar heretofore used and hence will fit within the opening A^8 in the magazine side bar A^4 and be properly guided in the longitudinal groove A^7 of the plate section A^5 as it is thrust thru or withdrawn 80 from the magazine. At one end, the bar G is 85 formed with an offset nose portion G^1 which is arranged to engage the latch E and rock it out of the path of the finger F^1 as the bar is shoved home, it being noted (see Fig. 1) that the bracket E^1 is recessed or cut away at E^4 , for the purpose presently to appear. A lug or stop 90 shoulder G^2 , formed on the bar G near the offset portion thereof, is adapted to engage the side of the magazine when the rod is shoved inwardly and serves to locate the rod 95 endwise in its active position. 100

The operation of the parts according to the foregoing arrangement will now be clear. When it is desired to remove the magazine A, the rod G is first inserted therein thru the opening A^8 in the side bar A^4 and pushed toward the right until the stop shoulder G^2 banks against the end of the top plate section A^5 to which it is opposed. The matrices are thus locked in the magazine against escape, and the nose portion G^1 will have engaged the latch E and moved the rear end thereof out of the path of the upstanding finger F^1 . The magazine is now free to be lifted safely out of engagement with the escapements C to the removing position indicated by the dotted lines in Fig. 2, this operation being accomplished in the manner before described by means of the side arms F^3 and the cam plate F^2 . As the magazine is raised, the nose portion G^1 is disengaged 11 from the latch E and the latter is allowed to resume its normal locking position under action of the spring E^2 . When the magazine is lowered, however, the nose G reengages the beveled corner E^4 of the latch and by such en- 12 13

gagement cams the latter out of the way so that the magazine may properly seat upon the escapement bar C². After the magazine comes to rest on the base frame D, the side arms F³ may be removed from the shaft F, if desired, and the rod G withdrawn from the magazine, the latch E thru the later operation being released and again restored to its active position by the compression spring E².

Having thus described my invention, its construction and mode of operation, what I claim is as follows:

1. In a typographical machine, the combination with a matrix magazine and a bank of escapements therefor, one of said parts being movable out of operative relation to the other, of a locking device to prevent such relative movement, and a movable bar operable at that side of the magazine adjacent the locking device for locking the matrices in the magazine, said bar being arranged to actuate said device as the bar is moved to and from its locking position.

2. In a typographical machine, the combination of a removable matrix magazine, a spring-actuated locking device for maintaining the magazine in operative position, and a movable matrix locking bar operable at that side of the magazine adjacent the magazine-locking device, said matrix locking bar being arranged to cooperate with the magazine-locking device in effecting the locking and unlocking of the magazine as the bar is moved from and to its active position, respectively.

3. In a typographical machine, the combination with a matrix magazine and a bank of escapements therefor, one of said parts being movable out of operative relation to the other, of a locking device to prevent such relative movement, and a removable matrix locking bar adapted to be inserted into and withdrawn from the magazine at that side thereof adjacent the magazine-locking device, said bar cooperating with said locking device to release or lock the magazine against removal according as the bar is inserted or withdrawn.

4. In a typographical machine, the combination of a removable matrix magazine, means for moving the magazine from its operative position to permit its removal, a locking device to prevent the operation of said moving means, and a removable matrix locking bar adapted to be inserted into or withdrawn from the magazine at that side thereof adjacent the magazine-locking device, said bar being arranged to cooperate with said locking device so as to effect the

locking and unlocking of the magazine as the bar is moved from and to its active position, respectively.

5. In a typographical machine, the combination of a removable matrix magazine, means for moving the magazine from its operative position to permit its removal, a spring-actuated locking device to prevent the operation of said moving means, and a removable matrix locking bar adapted to be inserted into and withdrawn from the magazine at that side thereof adjacent the magazine-locking device, said bar being adapted to engage and disengage the locking device as the bar is moved to and from its active position and to be operatively connected and disconnected with and from said device as the magazine is moved to and from its operative position.

6. In a typographical machine, the combination with a removable matrix magazine and a bank of escapements therefor, one of said parts being movable out of operative relation to the other, of a spring-actuated locking device to prevent such relative movement, and a removable matrix locking bar adapted to be inserted into and withdrawn from the magazine at that side thereof adjacent the magazine-locking device, said bar being formed with an offset portion arranged to engage and disengage the locking device so as to effect the locking and unlocking of the magazine as the bar is moved from and to its active position, respectively.

7. In a typographical machine, the combination with a removable matrix magazine and a bank of escapements therefor, one of said parts being movable out of operative relation to the other, of a spring-actuated locking device to prevent such relative movement, and a removable matrix locking bar adapted to be inserted into and withdrawn from the magazine at that side thereof adjacent the magazine-locking device, said bar being formed with an offset portion lying in the same plane and arranged to engage and disengage an exposed portion of the locking device as the bar is inserted and withdrawn, respectively.

8. A combination as specified in claim 6 characterized by the fact that the matrix locking bar therein referred to is formed with a stop shoulder for locating the bar longitudinally in its active position.

In testimony whereof, I have affixed my signature hereto.

JOHN R. ROGERS.
